Bennet Hotchkiss

UNITED STATES PATENT OFFICE.

BENNET HOTCHKISS, OF NEW HAVEN, CONNECTICUT.

IMPROVEMENT IN BLOWERS.

Specification forming part of Letters Patent No. 40,482, dated November 3, 1863.

To all whom it may concern:

Be it known that I, BENNET HOTCHKISS, of the city and county of New Haven and State of Connecticut, have invented new and useful Improvements in Fan-Blowers; and I do hereby declare the following to be a full, clear, and exact description of the construction and operation of the same when taken in connection with the accompanying drawings, which form part of this specification, in which—

Figure 1 is a side view. Fig. 2 is a longitudinal section. Fig. 3 is a transverse section.

Same letters of reference indicate like parts.

In the common fan-blower the blades or fans are large and never exceeding six in number, usually three or four. The air is drawn through openings in both sides of the shell or case, and discharged from an opening tangential to the circle described by the blades. In this manner of receiving and discharging the air by the use of such large blades the air forced before them (the blades) when released from the direct action of the blades, as it is when the blade passes the outlet, rebounds and is struck by the air before the next blade and produces a concussion, the rapid succession of which occasions the unpleasant noise always attending the use of such blowers. This concussion, together with the rotation of the air nearly around the case, consumes no small proportion of the power required to maintain the blast.

The object of my invention, therefore, is to produce a blower requiring much less power than the common blower, and at the same time noiseless in its operation.

It consists in an outward shell or case within which, upon an axis, I hang two wheels placed the required distance apart, (according to the size of the blower, I prefer about one-fourth the diameter of the wheels.) In the rims of these two wheels, and extending from the rim of one wheel to the rim of the other, I set and fix blades not exceeding in width one-twentieth the diameter of the wheels, and placed at a little distance apart, as more fully set forth hereinafter. I make the blades slightly convex upon one side and set them so that the convex side will be inclined outward from the wheel, the wheels to revolve in a direction opposite to the inclination of the

blades. The result is that air is drawn in through the center of the wheels to supply the vacuum occasioned by the revolution of the blades. The air passes from within the wheel out between the many blades into an air-chamber, and, owing to the peculiar form of the blades, the air is so rapidly forced from them and its place supplied by fresh air that very little, if any, rotation of the air takes place, but it is compressed into the air-chamber, from whence it may be conducted to places where the blast is required.

To enable others skilled in the art to make and use my improved blower, I will proceed to describe its construction and operation.

A is the shell or case inclosing the fan, and also forms the air-chamber.

B B are two wheels, fixed to an axle, C, which is made to revolve in bearings D D.

a a are blades fixed, one end into rim of each of the two wheels B B. I make these blades from thin sheet metal curved, as shown in Fig. 2, and set so that the convex side will face in the direction in which the wheel revolves, and inclined in the opposite direction, as shown in Fig. 2.

E is the driving-pulley fixed to the arbor C.

F are openings through the side of the shell to admit air to supply the blast.

H is the air chamber; I, the outlet. I place a partition, L, within the case, (see Fig. 3,) and between the fan and outlet, to form a passage from the air-chamber to the outlet. Red arrows denote the currents of air. When power is applied and the fans or blades revolving, the air which is before them is thrown off and a fresh supply drawn through the inlet. The air thus thrown off is forced into the air-chamber and through the outlet to the conductors. The nearer together the floats or blades are placed the narrower they may be, (but the width before mentioned experiments have proved to be about right,) provided, however, that they be so wide that a line drawn at right angles with and over one blade will strike the next blade back above its lower edge, as shown in Fig. 2, and but little more than this width must be used else the air will be rotated with the blades. In this manner a constant and steady draft is kept up between all the blades; consequently there cannot be rebound or concussion of the mov-

ing or compressed air, without which there can be no noise, as before shown, and the object of my invention fully accomplished an assertion warranted by numerous practical experiments proving the theory of my invention as herein set forth to be practically correct.

Therefore, having fully set forth my invention, I do not broadly claim a curved blade for fan-blowers, as such is not new; but

What I claim as of my invention, and new

and useful, and desire to secure by Letters Patent, is—

The blades *a a* when the same are of the form and set relatively to each other in the manner described, and combined with an air-chamber, *H*, inlets *F*, and outlet *I*, substantially as and for the purpose specified.

BENNET HOTCHKISS.
